UNITED STATES PATENT OFFICE.

MOSES S. SIMON, OF CINCINNATI, OHIO.

REGISTERING ATTACHMENT FOR BOTTLES.

SPECIFICATION forming part of Letters Patent No. 737,290, dated August 25, 1903.

Application filed July 2, 1902. Serial No. 114,114. (No model.)

To all whom it may concern:

Be it known that I, MOSES S. SIMON, a citizen of the United States of America, and a resident of Cincinnati, county of Hamilton, 5 State of Ohio, have invented certain new and useful Improvements in Registering Attachments for Bottles, of which the following is a specification.

The object of my invention is a device to 10 be attached to the neck of a bottle containing a beverage for registering the fact each time any of the liquid is poured from the bottle.

My invention is illustrated in the accompanying drawings, in which—

15 Figure 1 is a side elevation of the device embodying my invention attached to a bottle in the position it occupies when the stopper is seated in the neck of the bottle. Fig. 2 is a view, partly in side elevation and partly in 20 section, of the same in the position it occupies when the stopper is raised from the bottle. Fig. 3 is a sectional view taken upon line $z-z$, Fig. 1.

I will now describe the invention in connection with the accompanying drawings.

Referring to the parts, the housing A is secured to the neck of the bottle B by means of clips $a-a'$, which consist of split rings, having pivoted upon one of the split ends levers 30 a^2 , which have teeth for engaging the ends a^3 of the rings. By throwing the lever a^2 out of engagement with end a^3 the device may be readily removed from the bottle. A casing C is connected to the housing A by means of

35 a frame c. Casing C has at its bottom a horizontal slit c^2 for exit of disks D from the casing. Disks D are held down by means of the coiled spring E, bearing upward against the removable cap d of the casing. Disks D may 40 be thrown out of opening c^2 by a sliding plunger F, which reciprocates in the way f, which registers with slit c^2 . Plunger F is actuated to eject one of the disks from casing A by means of the vertical rod a^4 , which slides

45 within housing A and is kept in its normal position by a coiled spring a^6 . Rod a^4 is coupled to plunger F by means of a bell-crank lever f' , which has a fulcrum at f^2 upon the side of casing C. When rod a^4 is lowered, 50 the bell-crank lever is rotated upon its fulcrum, pushing plunger F outward and forcing the lowermost of the disks D out through

opening c^2 . Mounted upon top of casing C is a bell G, whose hammer g is carried by a lever g' , whose end projects down in the path 55 of the lever g^2 , pivoted upon frame c and engaged by the upper end of rod a^4 , so that when the rod a^4 is lowered to cause plunger F to eject disks D from casing C lever g^2 is actuated thereby to strike lever g' and to 60 sound the bell. Housing A has an upwardly-projecting arm a^5 , which carries a pin which engages lugs b, projecting from stopper b' of the bottle. Lugs b carry an arm b^2 , which is coupled by a link b^3 to arm a^4 , so that when 65 arm a^4 is lowered the stopper is rotated about arm a^5 , carrying it up out of engagement with the neck of the bottle.

The operation of my device is as follows: Whenever it is desired to pour out any of the 70 contents of the bottle B, lever a^4 must be actuated to raise the stopper out of the end of the neck. This movement causes plunger F to push disks D out of the casing C, and at the same time rings the bell, thus calling attention to the fact that some of the contents of the bottle have been emptied therefrom, and also registering the number of times, such actions being done by reason of diminution 75 of the number of disks, in casing C. 80

I have shown my invention in the best form known to me; but it is obvious that many mere mechanical changes might be made therein without departing from the scope of my invention. 85

What I claim is—

1. The combination with a bottle, of the casing containing disks and having an opening in it for the exit of the disks, means for securing the casing to the neck of the bottle, 90 a bell, a sliding rod mounted upon the side of the bottle, and means for coupling the lever to the casing and to the bell, so that the actuation of the lever simultaneously ejects a disk from the casing, and rings the bell. 95

2. The combination of the housing to be secured to the neck of the bottle, a sliding rod in the housing, a casing for containing disks secured to the housing, and having an opening in its bottom for the exit of the disks, 100 a plunger for ejecting the disks from the casing, a lever coupling the plunger and sliding rod, a bell and means for coupling the rod and the bell whereby when the rod is ac-

tuated the plunger ejects a disk from casing at the same time that the bell rings.

3. The combination of the sliding rod and a casing for containing disks mounted upon 5 the neck of the bottle, an opening in the casing for the exit of disks therefrom, a bell, a stopper seated in the neck of the bottle, means for coupling the stopper to the sliding rod, means for coupling the bell to the sliding rod, 10 a plunger for ejecting the disks from the casing, a means for coupling the plunger and the sliding rod whereby, upon the actuation of the sliding rod a disk is ejected from the casing, the bell is sounded, and the stopper is 15 raised simultaneously, substantially as shown and described.

4. The combination of the housing to be secured to the neck of the bottle, a casing secured to the housing for containing the disks 20 and having an opening therein for the discharging of the disks, a plunger for forcing

the disks out of the casing, a sliding rod mounted in the housing, a bell, a stopper in the neck of the bottle, a sliding rod in the housing, levers for connecting the plunger 25 the bell and the stopper each with the sliding rod, substantially as shown and described.

5. The combination of a housing and casing secured thereto, split rings secured to the housing, toothed levers pivoted to the end of 30 each ring to clamp it to the neck of the bottle, a sliding rod in the housing, a bell, a plunger for ejecting disks from the casing, and means for coupling the plunger and the bell each with the sliding rod, so that actuation thereof simultaneously rings the bell and 35 ejects a disk from the casing, substantially as shown and described.

MOSES S. SIMON.
